UNITED STATES PATENT OFFICE.

CHARLES PIPITONE, OF BROOKLYN, NEW YORK, ASSIGNOR, BY DIRECT AND MESNE ASSIGNMENTS, TO INTERLOCKING CONSTRUCTION CORPORATION, A CORPORATION OF NEW YORK.

INTERLOCKING BUILDING BLOCK.

Application filed May 27, 1922. Serial No. 564,189.

To all whom it may concern:

Be it known that I, CHARLES PIPITONE, a subject of the King of Italy, and a resident of New York, borough of Brooklyn, in the county of Kings and State of New York, have invented certain new and useful Improvements in an Interlocking Building Block, of which the following is a full, clear, and exact specification.

10 This invention relates to a class of articles of manufacture adapted to be used as a building material.

My invention has for its object primarily to provide a block designed to be utilized 15 for erecting buildings, walls and other structures, and which is molded preferably of cement, commonly known as concrete, in a form so that each block will interlock with the next adjacent block when a number are 20 erected in a row, the invention also contemplating the provision of a block having an exposed face molded and colored to represent laid brick or various kinds of stone, in order to facilitate the process of erection as well 25 as obtaining the advantages generally resulting from the use of concrete in structures. The block consists mainly of a body part of substantially a rectangular shape having in one of its ends a transverse groove, and on 30 the opposite end of the body part is a transverse extension member disposed on alignment with the groove as well as being smaller than the groove so that when a number of the blocks are laid in a row the blocks are interlocked by the extension members being interfitted in the grooves. On the front faces of 35 the body part and extension member is a plate having projecting spaced sections of formations which may represent structurally 40 erected brick or stone and all of these parts of the block are molded integrally from cementitious material.

A further object of the invention is to provide an interlocking block of a simple, efficient and durable construction which may be made in any appropriate shape and size.

With these and other objects in view, the invention will be hereinafter more fully described with reference to the accompanying 50 drawing forming a part of this specification in which similar characters of reference indicate corresponding parts in all the views, and will then be pointed out in the claims at the end of the description.

55 In the drawing, Figure 1 is a perspective

view of one form of interlocking building block embodying my invention.

Fig. 2 is a sectional view, partly in detail, taken through the block on the line 2-2 of Fig. 1.

Fig. 3 is a sectional view, partly in detail, taken crosswise through the block on the line 3-3 of Fig. 2, and

Fig. 4 is a fragmentary view, showing in perspective, the manner of interfitting two 65 of the blocks when used in the erection of a structure.

The block has a body part 10 which may be substantially rectangular in shape, and in the central portion of one end of the body part is 70 a transverse groove, as 11, while on the other end of the body part on alignment with the groove is a transverse extension member, as 12. This extension member is of a shape similar to the shape of the groove which is 75 slightly larger than the extension member. The body part 10 and the extension member 12 are made of cementitious material, such as cement commonly known as concrete of a class extensively used for erecting structures. 80

On the front face of the body part 10 may be a plate 13 which is also of cementitious material so that the plate and body part may be molded together when the block is made, and embedded in the block between the body part and the plate 13 may be a plate 14 of intersticed or perforated wire or sheet metal to cause the plate 13 to firmly adhere to the body part. The block may be molded so that its exposed face will represent erected 90 stone or laid brick, as illustrated, and to accomplish this the cementitious plate 13 is colored, for example, in red and molded to provide exposed protruding spaced sections 95 each of which is substantially rectangular as well as being of a size similar to the size of an ordinary brick. The block is preferably made of a size so that the sections 15 are six in number which are relatively disposed in spaced staggered relation representing three rows the usual form of laid brick, 100 as shown, and one of the sections of the central row terminates at one of the edges of the groove 11, while the second section of this central row terminates at the free end 105 of the extension member 12. Thus when two or more of the blocks are laid in a row, as shown in Fig. 4, the extension member 12 with its brick symbolized face is interfitted in the groove 12 of the next adjacent block, 110

and by laying rows of the interfitted blocks one upon another a building, wall or other structure may be erected which has the appearance of being laid of brick of the ordinary types.

Also embedded in the block in spaced relation to the intersticed plate 14 is a sheet element 16 which may be of asphalt or other waterproof material for preventing moisture from passing through the pores of the block, and on spaced parts of the intersticed plate 14 may be vertically disposed spaced bars, as 17 and 18. Extending from these bars are two rods 19 and 20 which are 10 embedded in the central parts of the body part 10, and these rods are disposed on longitudinal alinement toward the rear face of the body part. On the second end of each of the rods 19 and 20 is a hook or eye 21, and 15 the hooks are in register as well as being spaced from the rear face of the body part. In the registered hooks 21 of the rods 19 and 20 is a rod 22 of a length so that one of its ends terminate within the extension 20 member 12 of the body part 10, while the other end of the rod 22 terminates at the groove 11 of the body part. Embedded in the upper and lower parts of the body 10 may also be rods 23 and 24 which are 25 disposed above and below the rod 22, thus by the provision of the hooked rods 19, 20, with the rods 22, 23 and 24 the block is reinforced 30 against tendency to easily break or crumble.

In the foregoing description, I have embodied the preferred form of my invention, but I do not wish to be understood as limiting myself thereto, as I am aware that modifications may be made therein without departing from the principle or sacrificing 35 any of the advantages of this invention, therefore, I reserve to myself the right to make such changes as fairly fall within the scope thereof.

Having thus described my invention, I 40 claim as new and desire to secure by Letters Patent:—

1. An interlocking building block, comprising a substantially rectangular body part of cementitious material having in one 45 of its ends a transversely disposed groove and having on its other end in alinement with the groove a transverse extension member of smaller dimensions than the size of the groove, a plate of cementitious material 50 on the front facing of the body part, having protruding spaced sections colored and relatively arranged so as to represent a number of structurally laid bricks or stones, and an intersticed plate between the body part 55 and said colored plate.

2. An interlocking building block, comprising a substantially rectangular body part of cementitious material having in one 60 of its ends a transversely disposed groove and having on its other end in alinement 65

with the groove a transverse extension member of smaller dimensions than the size of the groove, a plate of cementitious material on the front face of the body, having protruding spaced sections colored and relatively arranged so as to represent a number of structurally laid bricks, an intersticed plate between the body part and said colored plate, and a substantially moisture proof sheet element embedded in the body in 70 spaced relation to the intersticed plate.

3. An interlocking building block, comprising a substantially rectangular body part of cementitious material having in one of its ends a transversely disposed recess and having on its other end in alinement with the groove a transverse extension member of smaller dimensions than the size of the groove, a plate of cementitious material on the front face of the body, having protruding spaced sections colored and relatively arranged so as to represent a number of structurally laid bricks, an intersticed plate between the body part and said colored plate, a substantially moisture proof sheet element embedded in the body in 80 spaced relation to the intersticed plate, and rods embedded in the body part so that they extend from the intersticed toward the rear face of the body part between its groove 85 and its extension member.

4. An interlocking building block, comprising a substantially rectangular body part of cementitious material having in one of its ends a transversely disposed groove and having on its other end in alinement with the groove a transverse extension member of smaller dimensions than the size of the groove, a plate of cementitious material on the front face of the body part, having protruding spaced sections colored and relatively arranged so as to represent a number of structurally laid bricks, an intersticed plate between the body part and said colored plate, a substantially moisture proof element embedded in the body in 90 spaced relation to the intersticed plate, rods embedded in the body part so that they extend from the intersticed toward the rear face of the body part between its groove 95 and its extension member.

5. An interlocking building block, comprising a substantially rectangular body part of cementitious material having in one of its ends a transversely disposed groove and having on its other end in alinement with the groove a transverse extension member of smaller dimensions than the size of the groove, a plate of cementitious material on the front face of the body part, having protruding spaced sections colored and 100

- relatively arranged so as to represent a number of structurally laid bricks, an intersticed plate between the body part and said colored plate, a substantially moisture proof sheet element embedded in the body in spaced relation to the intersticed plate, spaced metallic bars on the intersticed plate, extending from the underside to the top of the face of the body part, rods embedded in the body part so that they extend from the bars of the intersticed plate toward the rear face of the body part between its groove and its extension member, both of said bars having alined hooks on their free ends, a rod embedded in the body part and in its extension member, said rod being seated in the hooks, and rods embedded also in the body part one above and one below the hooked rods.
6. An interlocking building block, comprising a substantially rectangular body part of cementitious material having in one of its ends a transversely disposed groove and having on its other end in alinement with the groove a transverse extension member of smaller dimensions than the size of the groove, a substantially moisture proof sheet element embedded crosswise in the body from end to end, rods embedded in the body part so that they extend from the front face toward the rear face of the body part between its groove and its extension member, both of said bars having alined hooks on their free ends, and a rod embedded in the body part and in its extension member, said rod being seated in the hooks.
7. An interlocking building block, comprising a substantially rectangular body part of cementitious material having on one of its ends a transversely disposed recess and having on its other end in alinement with the groove a transverse extension member of smaller dimensions than the size of the groove, an intersticed plate embedded in the body in proximity to front face of the body, rods embedded in the body part so that they extend from the bars of the intersticed plate toward the rear face of the body part between its groove and its extension member, both of said bars having alined hooks on their free ends, a rod embedded in the body part and in its extension member,
- said rod being seated in the hooks, and two rods embedded also in the body part one above and one below the hooked rods.
8. An interlocking building block, comprising a substantially rectangular body part of cementitious material having in one of its ends a transversely disposed groove and having on its other end in alinement with the groove a transverse extension member of smaller dimensions than the size of the groove, an intersticed plate embedded in the body part in proximity to its front face, spaced metallic bars on the intersticed plate, extending from the underside to the top face of the body part, rods embedded in the body part so that they extend from the bars of the intersticed plate toward the rear face of the body part between its groove and its extension member, both of said bars having alined hooks on their free ends, and a rod embedded in the body part and in its extension member.
9. An interlocking building block, comprising a substantially rectangular body part of cementitious material having in one of its ends a transversely disposed recess and having on its other end in alinement with the groove a transverse extension member of smaller dimensions than the size of the groove, an intersticed plate between the body part and said colored plate, a substantially moisture proof sheet element embedded in the body in spaced relation to the intersticed plate, spaced metallic bars on the intersticed plate, extending from the underside to the top face of the body part, rods embedded in the body part so that they extend from the bars of the intersticed plate toward the rear face of the body part between its groove and its extension member, both of said bars having alined hooks on their free ends, a rod embedded in the body part and in its extension member, said rod being seated in the hooks, and two rods embedded also in the body part one below and one above the hooked rods.

This specification signed and witnessed this 26 day of May A. D. 1922.
